TYPOGRAPHICAL COMPOSING MACHINE

Frank C. Frolander, Elizabeth, N. J., assignor to
Mergenthaler Linotype Company, a corpora-
tion of New York

Application December 22, 1936, Serial No. 117,119

17 Claims.

(Cl. 199—25)

This invention relates to a power operated mechanism for typographical machines, such as a key-board mechanism of the class illustrated in U. S. Letters Patent No. 530,931, to P. T. Dodge.

5 A key-board mechanism of this class ordinarily comprises a series of pivoted power-driven cam yokes adapted to actuate a series of vertical reeds or bars, which in turn operate the escapements controlling the release of the matrices from the magazines. Each cam yoke is normally held in inactive position by a trigger actuable by a finger-key and, when moved, trips the cam yoke to allow the cam to engage and be rotated by a power-driven roll to swing the yoke about its 10 pivot and operate the reed, the trigger returning in the meantime to its normal position to arrest and maintain the yoke in inactive position after its operation of the reed. It sometimes happens, however, that the trigger fails to return to its normal position in time to arrest the yoke, so that the cam is permitted to engage the power 15 operated roll continuously and actuate the yoke more than once. The failure of the trigger to return to its normal position may be caused either by some mechanical abnormality or by an 20 unintentional prolonged depression of the finger-key.

It is the object of the present invention to overcome the foregoing and other difficulties, 25 and, to this end, the invention contemplates the provision of safety means operable upon the abnormal operation of the trigger to arrest the cam yoke after a single operation of the escapement actuating reed. More specifically, the trigger 30 is provided with a spring-pressed relatively movable dog adapted to yield when the trigger is moved by the depression of the finger-key to allow the cam yoke to fall by gravity to bring the cam into engagement with the power-driven 35 roll and, subsequently, when the yoke is raised by the cam to actuate the reed, to snap back into position to arrest the cam yoke in its inactive position upon the failure of the trigger to return to its normal position.

40 In the accompanying drawings, the invention is shown merely by way of example and in preferred form, and as applied to a mechanism of the class stated, but obviously many variations and modifications may be made therein, and in 45 its mode of application, which will still be comprised within its spirit. It is to be understood, therefore, that the invention is not limited to any specific form or embodiment except insofar as such limitations are specified in the appended 50 claims.

Referring to the drawings:

Fig. 1 is a vertical section, partly broken away, showing the improvements embodied in the key-board mechanism of a typographical machine;

Fig. 2 is a side elevation of a cam yoke and cam, partly broken away to show the construction;

Fig. 3 is a top plan view of a cam yoke and cam;

Figs. 4, 5 and 6 are detached views of the cam 10 yoke and associated parts, partly broken away and showing the parts in different stages of operation;

Fig. 7 is a view taken on the line 7—7 of Fig. 4, looking in the direction of the arrows;

Fig. 8 is a disassembled perspective view of the trigger; and

Fig. 9 is a disassembled perspective view of the safety dog.

As usual, the matrices A are released from their magazine B by escapements C, which are operated through a bank of pivoted levers D by a series of vertically movable rods or reeds E, suitably guided in the framework and constantly urged downward by strong springs (not shown). The upward movements of the reeds against the actions of their springs are effected by horizontally disposed yokes F, arranged as customary in a bank or series and with their inner ends positioned to engage the lower ends of the reeds. At 20 their opposite ends, the yokes are formed with vertically open slots F¹ which fit over a transverse pivot wire or rod F² in the framework, being removably held in position against the rod F² by spring detents F³ exerting a downward 25 pressure thereon; and between their ends, the yokes are provided with rotary cams or eccentrics G, pivoted thereto as at G¹ and adapted to be rotated by the underlying power-driven roll H, there being one roll for the entire series of yokes. 30 At their inner ends, the yokes F are supported upon angular pivoted dogs or triggers J whose free ends underlie and engage supporting ledges F⁴ on the yokes to hold the latter at such height as to maintain the cams G out of engagement 35 with the roll H, the cams in this position of the parts being held against rotary motion by the engagement of crosspieces G² thereon with fixed stops G³ on the framework. When, however, the triggers J are moved out of engagement with the 40 ledges F⁴, the cam yokes are tripped and allowed to drop, with the result that the cams G are disengaged from the stops G³ and come into contact with the roll H, causing the cam yokes to be reciprocated in the usual manner. The trig- 45

gers J are controlled by vertical bars K slidably arranged in the framework and operated by depressible finger-key levers L, the triggers being in constant operative connection with the finger-
5 keys through the bars K.

The parts so far described, and their mode of operation, are substantially the same as embodied in the commercial "Linotype" machine.

In carrying out the invention, each trigger J 10 is recessed as at J¹ (see Fig. 8) to accommodate a dog J², pivoted thereto as at J³ and formed with an opening J⁴ through which projects a cross pin J⁵ of smaller diameter carried by the trigger. In a space provided between the front 15 edge J⁶ of the dog J² and a wall J⁷ of the trigger J, there is arranged a torsion spring J⁸ having one end anchored in a hole formed in a raised boss J⁹ provided on the trigger and its other end anchored in a hole formed in the front edge J⁶ 20 of the dog J². The torsion spring J⁸ exercises itself to maintain the dog J² in its rearward position with the free or yoke supporting ends of the trigger J and dog J² spaced apart, as shown in Figs. 4 and 6, and yet allows the dog J² to 25 yield forwardly to bring the free ends of the trigger and dog closer together, as shown in Fig. 5, the pin J⁵ acting as a stop in both directions and the opening J⁴ determining the range of relative movement.

30 The yoke F is slightly modified to cooperate with the improved form of trigger J with its safety dog J² by the provision of a crosspiece F⁵ formed on the underside of the yoke to engage the safety dog J² and cause the same to yield in the release of the yoke (Fig. 5) and also to 35 engage the dog for the arrest of the yoke after its operation under abnormal conditions (Fig. 6).

In operation, when the finger-key L is depressed and rocks about its pivot L¹, it raises 40 the vertical bar K and rocks the trigger J clockwise (compare Figs. 4 and 5). In so doing, the dog J² strikes the crosspiece F⁴ on the yoke F and yields against the action of the spring J⁸ until the supporting end of the trigger is moved out 45 of engagement with the ledge F⁴ on the yoke. In this condition of the parts (see Fig. 5), the yoke is free to drop by gravity to bring the cam G into engagement with the power roll H, disengaging the crosspiece G² on the cam from 50 the stop G³. The roll H immediately effects the rotation of the cam G in the direction of the arrow, swinging the yoke upwardly to operate the reed E as the cam runs onto its high portion G⁴ and carrying the forward end of the yoke 55 above the ends of the trigger J and dog J². As soon as the crosspiece F⁴ on the yoke moves out of engagement with the dog J², the spring J⁸ exercises itself to return the dog to its original position, relatively to the trigger J, such that 60 upon the failure of the trigger to return to its normal yoke supporting position before the cam G completes its rotation, the crossbar F⁵ will bank upon the end of the dog J² and arrest the yoke slightly above its normal position (see Fig. 6), the cam G being brought to rest by the engagement of its pin G² with the stop G³ as usual. The dog J² will continue to support the yoke until 65 the trigger J is returned to its normal position, where it will underlie the ledge F⁴ and be ready to support the yoke as the dog J² is carried with it out of engagement with the crosspiece F⁴ (see dotted lines in Fig. 6). It will be understood, of course, that the dog J² becomes operative only when the trigger J fails to return to its normal position in time to arrest the downward 70

movement of the yoke F after the cam G has completed its rotation. Under normal conditions, the trigger will always return to normal position and the parts will operate in the usual way and as if the dog J² were not present. 5

As already stated, the preferred embodiment of the invention has been shown and described merely by way of example and in its specific application to the key-board mechanism of a "Linotype" machine. Obviously, however, it is 10 equally applicable to other finger-key controlled power-operated mechanisms, such as typewriters and the like, power shifts for the magazines of typographical machines, or other mechanisms wherein a single operation in response to the 15 actuation of the finger-key is desired or required. Moreover, it is applicable to power operated mechanisms controlled otherwise than by a finger-key, as, for example, teletypewriting and teletypesetting machines, wherein a perforated 20 tape control is substituted for the usual manual key-control.

Having thus described my invention what I claim is:

1. A power operated mechanism for typographical machines including, in combination, an actuating element, means for operating said element, control means for normally maintaining said operating means inactive and operable periodically to render said means active to inaugurate the operation of the actuating element, and safety means operable, upon the abnormal operation of said control means, to act independently of the control means to arrest the operating means after its operation of the actuating element. 25

2. A combination according to claim 1, wherein the safety means is adapted to yield to permit the release of said operating means and to be self-operative thereafter to condition itself 40 to arrest said means after the operation of the actuating element thereby.

3. A combination as in claim 1, wherein the safety means is adapted to yield to permit the release of said operating means and thereafter 45 automatically condition itself to arrest said means after the operation of the actuating element thereby.

4. A power operated mechanism for typographical machines including, in combination, 50 an actuating element, a normally inactive cam yoke pivotally mounted at one end and free at the other, a rotatable cam carried by the yoke for actuating the same to operate said element once during each rotation of the cam, means arranged to prevent rotation of the cam in the inactive position of the yoke, power means for rotating the cam, movable means normally engaged with the free end of the yoke to support it in inactive position, means operable to shift 55 said movable means from its supporting position to allow the yoke to swing from its inactive position to release the cam for operation and bring it into engagement with its rotating means, and safety means operable upon the failure of the 60 yoke supporting means to return to its supporting position to act independently of the yoke supporting means to arrest the yoke in inactive position after its operation of the actuating member. 70

5. A power operated mechanism for typographical machines including, in combination, an actuating element, a normally inactive cam yoke pivotally mounted at one end and free at the other, a rotatable cam carried by the yoke 75

for actuating the same to operate said element once during each rotation of the cam, means arranged to prevent rotation of the cam in the inactive position of the yoke, power means for 5 rotating the cam, movable means normally engaged with the free end of the yoke to support it in inactive position, means operable to shift said movable means from its supporting position to allow the yoke to move from its inactive position to release the cam for operation and bring it into engagement with its rotating means, and a safety dog adapted to be rendered operable upon the failure of the yoke supporting means to return to its supporting position to act independently of the yoke supporting means to arrest the yoke in inactive position after its 15 operation of the actuating element.

6. A combination according to claim 5, wherein the safety dog is carried by the yoke supporting means.

7. A combination according to claim 5, wherein the safety dog is carried by the yoke supporting means and is mounted to yield to permit the shifting of the supporting means in releasing 25 the yoke.

8. A combination according to claim 5, wherein the safety dog is carried by the yoke supporting means and is mounted to yield to permit the shifting of the supporting means in releasing 30 the yoke, and means to render the safety dog operative automatically thereafter to arrest the yoke in inactive position after its operation of the actuating element.

9. A finger-key controlled power operated mechanism including, in combination, an actuating element, a horizontally disposed cam yoke pivotally mounted at one end and free at the other, a rotatable cam carried by the yoke for actuating the same to operate the actuating element once during each rotation of the cam, a stop arranged to prevent rotation of the cam when the yoke is in horizontal position, a power-driven roll for rotating the cam, a trigger arranged normally to engage and support the 40 free end of the yoke, a finger-key depressible to move the trigger out of engagement with the yoke and allow the latter to drop to disengage the cam from the stop and bring it into engagement with the power-driven roll, and a safety 45 dog carried by the trigger and operative upon the failure of the trigger then to return to its normal position to support the yoke in horizontal position after its operation of the actuating element.

50 10. A key-controlled power operated mechanism including, in combination, an actuating element, a horizontally disposed cam yoke pivotally mounted at one end and free at the other, a rotatable cam carried by the yoke for actuating the same to operate the actuating element once during each rotation of the cam, a stop arranged to prevent rotation of the cam when the yoke is in horizontal position, a power-driven roll for rotating the cam, a trigger arranged 55 normally to engage and support the free end of the yoke, a finger-key depressible to move the trigger out of engagement with the yoke and allow the latter to drop to disengage the cam from the stop and bring it into engagement with the power-driven roll, said trigger being returnable to its normal yoke supporting position by the release of the finger-key, and a safety dog carried by the trigger and mounted to yield relatively thereto, said dog 60 being adapted to support the yoke in horizontal 65 position.

tal position after its operation of the actuating element upon the failure of the trigger then to occupy its normal position, whereby the cam will be arrested by its stop at the completion of one rotation thereof and a second operation of the yoke thus prevented until the trigger returns to its normal position.

11. In or for a finger-key controlled power operated mechanism including an actuating element and a pivotally mounted member for operating said element, a trigger movable from its normal position in response to the actuation of the finger-key to release said member for operation and returnable upon the release of the finger-key to arrest the member after its operation of the actuating element, said trigger being provided with a safety dog adapted to be operable upon the failure of the trigger to return to its normal position to arrest said member after its operation of the actuating element.

12. In or for a finger-key controlled power operated mechanism including an actuating element and a pivotally mounted member for operating said element, a trigger movable from its normal position in response to the actuation of the finger-key to release said member for operation and returnable upon the release of the finger-key to arrest the member after its operation of the actuating element, said trigger being provided with a yieldable safety dog pivoted thereto and adapted to be operable upon the failure of the trigger to return to its normal position to arrest said member after its operation of the actuating element.

13. In or for a finger-key controlled power operated mechanism including an actuating element and a pivotally mounted member for operating said element, a trigger movable from its normal position in response to the actuation of the finger-key to release said member for operation and returnable upon the release of the finger-key to arrest the member after its operation of the actuating element, said trigger being provided with a yieldable safety dog pivoted thereto and adapted to be automatically operable upon the failure of the trigger to return to its normal position to arrest said member after its operation of the actuating element.

14. In or for a finger-key controlled power operated mechanism including an actuating element and a pivotally mounted member for operating the actuating element, a trigger movable from its normal position in response to the actuation of the finger-key to release said member for operation and returnable upon the release of the finger-key to arrest the member after its operation of the actuating element, said trigger being provided with a yieldable spring-pressed safety dog pivoted thereto and adapted to be automatically operable upon the failure of the trigger to return to its normal position to arrest said member after its operation of the actuating element.

15. A finger-key controlled power operated mechanism comprising an actuating element, means for operating said element, and means operative in response to the depression of a finger-key to inaugurate the operation of said actuating element, said means being in constant operative connection with the finger-key and constructed and arranged to render the operating means operative to actuate the element but once for each depression of the finger-key.

16. A mechanism according to claim 15, wherein the means operative to inaugurate the oper-

ation of said actuating element comprises a composite member including two relatively movable sections adapted to render the actuating element inoperative, one section being active when 5 the finger-key is depressed and the other when the finger-key is released.

17. A finger-key controlled power operated mechanism comprising an actuating element, a cam yoke arranged to operate said element, 10 means for operating the cam yoke, and a trigger operative in response to the depression of a fin-

ger-key to release the cam yoke for operation of the actuating element, said trigger being provided with a relatively movable dog and both adapted to engage the cam yoke and hold it in inoperative position, the trigger being active 5 before the finger-key is depressed, and the dog being active after the finger-key is depressed and the cam yoke actuated to effect one operation of the actuating element.

10

FRANK C. FROLANDER.
